CLAIM

The ornamental design for a ceiling hanger, as shown and described.

DESCRIPTION

FIG. 1 is a front elevational view of a ceiling hanger showing my new design, the opposite rear elevational view being substantially identical;

FIG. 2 is a top plan view of the ceiling hanger of FIG. 1;

FIG. 3 is a right side view of the ceiling hanger of FIG. 1, the opposite left side view being substantially identical; and,

FIG. 4 is a bottom plan view of the ceiling hanger of FIG. 1.
